et al.

UNITED STATES PATENT OFFICE

FARRINGTON DANIELS, OF MADISON, WISCONSIN

SHAVING CREAM TUBE

Application filed August 31, 1928. Serial No. 303,258.

This invention relates to an improved type of tube for containing shaving cream, or the like, and has for its object the production of a tube adapted for use with a non-lathering 5 shaving cream, the cream being spread over the face directly from the end of the tube without the use of a shaving brush.

The invention will be fully understood from the following description and accompanying drawings in which,

Figure 1 is a perspective view of the tube; Fig. 2 is a detailed section of the head end of the tube; Fig. 3, a detailed section of an alternative form of the head end of the tube; 5 Fig. 4, an end view of the tube, and Figs. 5, 6, 7 and 8, detailed views of an alternative device used for sealing the tube. Fig. 5 is a section of the head end of the tube; Fig. 6, a view of the head as viewed from the inside 0 of the tube; Fig. 7 is a vertical plan view showing a detail of the sealing plug, and Fig. 8, an end view of the head with the sealing plug removed.

Referring to the drawings, it will be seen 5 that the tube consists of a cylindrical body portion 1 and a head 2 formed integrally therewith.

As shown in Figs. 2 and 3, the head is of saucer-like shape, the central portion being 0 flat and the outer edges being curved to form a rounded junction with the side walls of the tube. The amount of curvature of the outer edges may be varied within rather wide limits. In some instances, for example, it 5 has been found desirable to curve the outer edges sufficiently to leave the flat portion only about half the diameter of the tube.

The central flattened portion of the tube 0 may contain a number of corrugations or protrusions 3 which serve to roughen the surface to facilitate spreading the cream over the face. These protrusions may be stamped into the head portion of the material before the tube is pressed into final form. If desired, the flat surface of the head may be roughened in another manner, as shown in Fig. 3. In this form, the face of the head is painted with a mixture of cork-dust and cellulose lacquer, as shown at 4; or, if desired, a layer of roughened rubber may be cemented

on the face of the head instead of using the layer of painted cork-dust.

As shown in Figs. 2 and 3, the head contains an outlet orifice 5 through which the cream is squeezed from the tube onto the face 55 of the head. The orifice is cut out of the metal piece 12 which forms a portion of the body of the head lying wholly within the plane of the spreading surface. It is internally threaded and is sealed by the externally 60 threaded screw plug 6, as shown. When the plug is screwed into the outlet a small amount of paste is extruded from the crevices of the threads and tends to form a self-sealing joint with the shoulder of the plug. The 65 surface of the head immediately around the outlet orifice which contacts with the shoulder of the lug 6 is left smooth to form a flush contact.

In the form shown in Figs. 5 to 8, the outlet 70 orifice is in the form of a keyhole slot 7. The slot is formed in a portion of the metal 8 forming the head 2, and, as in the form first described, is entirely within the spreading surface of the head. The metal portion 8, 75 as shown in Figs. 5 and 7, has a keyhole slot which divides it into oppositely disposed semi-cylindrical pieces having portions of their end surfaces cut to form inclined faces 9. The inclined faces 9 co-operate with the 80 projections 10 of the sealing plug 11. These projections have inclined faces formed to contact with the faces 9 so that when the plug is inserted in the slot and rotated slightly a 85 wedging action is produced which serves to grip the plug securely in place.

The form of the head makes it particularly 90 well adapted for spreading the cream over the face. The plug is removed, the tube 95 squeezed slightly to extrude a strip of cream onto the roughened face of the head and is then spread over the face by merely rubbing with the tube, much as in the manner of spreading with a brush, the curved edge portions of the head eliminating any sharp edges over which the cream might be pushed and wasted. After being used, the plug is inserted to seal the outlet and any remaining portion of the cream may be readily rinsed 100

from the face of the head or the sides of the plug.

While the tube is shown collapsible, permitting the cream to be expressed therefrom in a well-known manner, the invention is not limited to a collapsible tube. Any suitable tube construction provided with paste-expressing means may be employed.

The term "end wall" employed in the appended claims is to be construed to determine the actual end wall of a container and not any device which may be attached to the container to provide a roughened surface spaced from the actual end wall of the container. Thus, devices which may be screw-threaded into the discharge openings of containers to provide spreading surfaces spaced from the end walls of the containers are not included in the term "end wall" as it is employed in the appended claims.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. A container for shaving cream comprising a tube having one end closed with a corrugated head, an outlet for the cream being located in the surface of said head, and means for sealing said outlet, said sealing means being secured in said head in such manner that upon its removal, a substantially flat surface is available for spreading of the cream.

2. A shaving cream tube for expressing cream and having an end-wall of substantially the same diameter as the container and merging by means of rounded corners with the cylindrical walls of the casing, said end-wall having an outlet passage therethrough and having a roughened outer surface adapted to serve as a brush in applying the cream to the face.

3. A tube of the character described having an apertured end-wall substantially equal to the diameter of the tube, the outer surface of said wall being substantially flat and roughened to provide a spreading surface, and a closure member for the aperture in said end-wall.

4. A tube of the character described comprising a side-wall; and an apertured metallic end-wall formed integral therewith, the metal of said wall being roughened on the outer side to form a spreading surface.

5. A collapsible tube having a side wall and an end wall, said end wall being substantially equal in area to the cross-sectional area of the tube, and being of the same shape as the body of the tube, said end wall having a substantially flat central portion, said

flat portion being roughened on its outer surface and being apertured.

6. A collapsible tube having a side wall and an end wall, said end wall being substantially equal in area to the cross-sectional area of the tube, and being of the same shape as the body of the tube, said end wall having a substantially flat central portion, said flat portion being coated to provide a roughened surface.

FARRINGTON DANIELS.
